(57) **CLAIM**

The ornamental design for a vehicle display sign, as shown and described.

DESCRIPTION

FIG. 1 is a front elevational view of the vehicle display sign of the present invention;

FIG. 2 is a rear elevational view of the vehicle display sign of FIG. 1;

FIG. 3 is a left side elevational view of the vehicle display sign of FIG. 1;

FIG. 4 is a right side elevational view of the vehicle display sign of FIG. 1;

FIG. 5 is a top plan view of the vehicle display sign of FIG. 1; and,

FIG. 6 is a bottom plan view of the vehicle display sign of FIG. 1.

The broken lines showing of the word logo in FIGS. 1 and 2 are for illustrative purposes only and form no part of the claimed design.
